CORNER CONSTRUCTION FOR FULL-FASHIONED HOSIERY

Ervin S. Sachsenmaier and Edmund J. Butler,
Cordelle, Ga., assignors to Maywood Silk Hosiery Mills, Inc., Cordelle, Ga., a corporation of Georgia

Application January 31, 1941, Serial No. 376,746

12 Claims. (Cl. 66—182)

This present invention relates to full fashioned hosiery and especially to an improvement at the junction of the high heel, low heel, and upper sole usually referred to as the corner of the topping line. In full fashioned knitting, it is common practice to knit the leg blank on one machine called the legger and transfer this blank to another machine called the footer for the knitting of the foot. The transfer is accomplished by an intermediate operation called topping. This operation has in the past required a great amount of skill due to the necessity of properly placing every loop in the topping line on the topping points.

At each end of the topping line there are several reinforced loops which, due to their heaviness, are very difficult to run on the points. Any loops which are not properly placed on the points will cause a defect in this area which is very difficult to detect. If a loop should be missed or even split, a defect will appear in the finished stocking which cannot be detected until the stocking has been subjected to considerable strain.

It is an object of this invention to lock or selvedge these reinforced loops in such a manner that improperly transferred loops cannot cause a run in this area and impair the usefulness of the stocking.

This locking or selvedging of the reinforced loops is accomplished by transferring said reinforced loops to a wale or wales of the low heel and locking them by the continued knitting of the low heel. The invention also contemplates the transfer of the heel to the reinforced loops in such a manner that continued knitting will lock the reinforced loops of the topping area.

Some of the objects of the invention having been stated, other objects will appear as the description proceeds, when taken in connection with the accompanying drawings, in which—

Figure 1 is a plan view of a lower portion of a stocking, embodying the present invention;

Figure 2 is a plan view of the lower portion of the stocking shown in Figure 1 prior to the looping and seaming operations which are necessary for uniting the edges;

Figure 2A is a sectional view taken along the line 2A—2A in Figure 2;

Figure 3 is a plan view of the lower portion of the stocking leg and heel tabs prior to the topping operation and placing the same upon a footer for knitting the foot portion thereto to produce a stocking such as shown in Figure 2;

Figure 4 is an enlarged detail view showing the

construction at the junction of the lower edge of the leg portion and the heel tabs;

Figure 5 is an enlarged view similar to Figure 4, but showing a slightly modified form of construction;

Figure 6 is a view similar to Figures 4 or 5 showing still another modified form of gore construction;

Figure 7 is an enlarged view similar to Figures 4, 5 or 6, showing still another modified form of gore construction.

Figure 8 is an enlarged view showing another form of corner construction wherein the unreinforced loops of the leg blank are employed to lock the reinforced loops;

Figure 9 is an enlarged view similar to Figure 8, showing the reinforced area extending below the topping line but locked by means of unreinforced loops;

Figure 10 shows another variation in which there are successive transfers or locking operations employing unreinforced loops as well as reinforced loops.

Referring more particularly to the drawings, 25 the numeral 10 broadly designates the lower portion of a full fashioned stocking after it has been completed. This stocking has conventional body or leg portion 11, heel portion 12 and foot portion 14. Usually the leg portion is narrowed as at 15, and the foot portion is narrowed as at 16 to give the proper shape to the finished stocking.

At the junction point of the leg portion 11, the heel portion 12 and the foot portion 16, there is 35 a critical point called the gore or corner of the stocking which is designated by the reference character 17. As heretofore stated, much difficulty has been experienced in the construction at this point, due to the fact that the topping operations have been subject to imperfect work. Figures 2 and 3 of the drawings have been made to show the steps employed in producing the stocking. The leg portion 11 is first knitted on the legger machine and upon reaching the lower portion thereof (see Figure 3) an additional reinforced area is usually provided at the heel. For example, beginning as at 18, reinforcing strands 46 are introduced which extend inwardly to lines 19 from opposed edges of the stocking.

Upon reaching topping line 20, a few additional courses are knitted onto the lower edge of the leg portion forming ravel courses 21. These ravel courses are used for facilitating the topping operation, but after the stocking has been placed

upon the topping machine points, this excess portion 21 is removed.

The leg portion has knitted integral with the lower edge thereof, spaced heel tabs 12 which likewise have reinforcement 46 therein, and upon the completion of the heel tabs, suitable loose courses 22 are provided near the lower edges for looping these edges together in a subsequent operation to be performed after the stocking blank is completed. Suitable spread sinker wales 23 are also provided along the proximate edges of the heel tabs. These loose wales, along with loops in the topping line 20 are placed upon the topping machine points, thence to the transfer bar and then placed in a machine called a footer, after which the foot portion of the stocking is knit to form a stocking blank such as shown in Figure 2.

It will be noted that the topping line 20 extends into the reinforced area to the loose wales 23, thus making it necessary under ordinary circumstances to place one or more reinforced loops upon the topping points. In Figure 4, an enlarged detail view of the gore area or corner is shown illustrating the means which is employed in the present invention for eliminating the defects which occur from placing loops having a plurality of strands upon topping points. Also it will be seen by referring to Figure 2A that a flap 12a is disposed along the edge of each heel tab after the foot portion has been united thereto along topping line 23. This flap is normally disposed on the inside of the finished stocking and is employed in the present invention to serve as an edge to which transferred reinforced loops can be attached.

For convenience of description in Figure 4, the wales of the stocking have been numbered 26 to 33 inclusive, and the courses numbered 34 to 48 inclusive. The same course and wale numbers apply also to the modified forms of the invention shown in Figures 5, 6, 7, 8, 9 and 10. It will be noted that the body portion is knit with a single strand or a plurality of strands designated by the reference character 45; whereas the high heel and heel tabs have the strand 45 supplemented by a reinforcing strand 46. This reinforcing strand is usually disposed throughout the heel tab, and in Figure 4 is shown extending along two wales along topping line 20 into the leg portion beyond the inner edges of the heel tabs. In other words, the reinforcing strand in Figure 4 is disposed in wales 26, 27, 28, 29 and 30; whereas, the heel tab extends only through wale 28. As heretofore stated, much difficulty has been encountered in placing the loops on the topping points where a reinforcing strand or strands are employed, because it often results in a split loop which will produce a weak place in the stocking and in many cases produce a run.

In the present form of the invention, this difficulty is eliminated by locking the reinforcing loops which extend into the body portion of the stocking along the topping line into the adjacent wales of the heel tabs. For example, the reinforcing strand 46 extends through wales 26, 27, 28, 29 and 30 at the course 36. Since the body portion of the stocking leg stops off at this course and is topped onto the topping machine, it has been found desirable to transfer the loops in wales 29 and 30 to wales 27 and 28, respectively, in course 31 of the heel tabs, where they are locked by the continued knitting of the heel tab. By providing this type of construction, a split loop during transfer to the foot bar points will not

produce a run in the transferred courses, although it might weaken to a slight degree the stocking at this point.

Figure 5 illustrates corner construction 17a which is very similar to Figure 4, except that the reinforcing strand 46 is transferred from wales 29 and 30 at course 39 to wales 27 and 28 at course 39. The only difference in this form and the preceding form, is that the reinforcing loops are transferred at a point several courses after the topping line whereas in the preceding form, the reinforcing loops are transferred laterally and locked in the next succeeding course.

In Figure 6, a corner construction 17b is illustrated. The reinforcing loops of wales 29 and 30 are transferred laterally to a single loop in wale 28 of course 39. This form of construction might be most desirable in many instances, because it produces a smaller amount of crinkling in the finished fabric; however, the crinkling is ordinarily insufficient for normal detection from the observer's eye, even when individual wales received the transferred loops.

Figure 7 shows still another modified form of the invention 17c in which the entire heel tab is transferred inwardly. In other words, this type of construction amounts substantially to a narrowing of the stocking at this point. In any event, the wales 27 and 28 merge into wales 29 and 30 at course 38 thereby causing the wales 29 and 30 to be locked in the continued knitting of the heel.

In the drawings, the high heel of the stocking is shown as beginning at 18 and as the knitting of this leg portion progresses, the high heel is knitted until the corner or gore of the stocking has been reached. The high heel portion is formed by knitting a reinforcing strand in the leg portion. This same reinforcing usually continues throughout the spaced heel tabs, which tabs are knitted onto the leg portion immediately below the high heel areas. In the claims the reinforced areas above the topping line 20 are referred to as the leg portion of the stocking because of the high heel portion.

Figure 8 shows an enlarged detail 17d employing a slightly different means for locking the reinforced loops in wales 29 and 30 at course 38. The drawings show the reinforced loops at these points formed from main strand 45 and a reinforcing strand 46. In order to lock these loops, the main or unreinforced strand 45 is knitted independently for one course, below the topping line 20 and upon the succeeding course these independent reinforced loops are transferred into adjacent loops in the heel gusset. In other words, only the unreinforced strand 45 is knitted in wales 29 and 30 at course 37, and at course 38, the unreinforced wales 29 and 30 are locked into wales 27 and 28 during the continued knitting of the stocking blank.

In Figure 9, an enlarged detail 17e is shown employing the same principle employed in Figure 8, because the unreinforced loops are employed to lock the reinforced loops by a transfer operation. However, in this form the wales 29 and 30 are reinforced by strand 46 through courses 37 and 38, which courses are disposed below the topping line 20. At course 39, the reinforcing strand 46 is omitted in wales 29 and 30 and at these points, the loops of unreinforced strand 45 are transferred to wales 27 and 28, where they are locked during the continued knitting of the stocking blank.

In Figure 10 an enlarged detail 17f is shown

employing successive transfers for locking the reinforced loops at the corner of the hosiery blank. It is here seen that four wales, namely 29, 30, 31 and 32 are locked in the heel gusset during the continued knitting of the leg blank. In other words, only the unreinforced strand 45 is disposed in wales 31 and 32 at course 37; and these wales are transferred from course 36 and locked in course 37 to reinforced wales 29 and 30, respectively. The reinforced wales contain strands 45 and 46 therein, however, it is to be understood that one or more reinforcing strands can be employed in any form of the invention without departing from the basic principle involved. The reinforced wales 29 and 30, are in turn transferred from course 37 and locked in wales 27 and 28 at course 38 thereby causing all four of the wales 29 and 30, 31 and 32 to be locked in the two wales 27 and 28 of the heel tab at points below the topping line.

In the above described variations of the invention, there is a common structural similarity, namely, the locking or selvedging of normally unlocked or unselvedged loops in the leg blank. As previously pointed out, the locking of the unselvedged loops not only reinforces the stocking at the corner, but also eliminates to a large degree, the bad effects of improper transfers. Transfers are necessary to complete a stocking where double unit construction is employed.

In the drawings and specification there has been set forth a preferred embodiment of the invention, and although specific terms are employed, they are used in a generic and descriptive sense only and not for purposes of limitation, the scope of the invention being set forth in the appended claims.

We claim:

1. In a full fashioned hosiery blank comprising a leg portion knitted from a plurality of transverse courses, a heel tab knitted from a plurality of relatively short transverse courses onto the leg portion said heel tab being formed by the continuation of the wales of the leg portion and having one edge thereof normally disposed substantially at right angles to the ravel edge whereby coursewise and walewise topping lines can be provided in parallel relation to the ravel and heel tab edges respectively, reinforcing strands interknitted in said leg portion and the heel tabs, said strands extending into adjacent wales on each side of said walewise topping line, some of the reinforced wales between the walewise topping line and said heel tab edge being connected by transferred loops to adjacent wales at a course below said ravel edge topping line.

2. In a full fashioned hosiery blank comprising a leg portion knitted from a plurality of transverse courses, a heel tab knitted from a plurality of relatively short transverse courses onto the leg portion said heel tab being formed by the continuation of the wales of the leg portion and having one edge thereof normally disposed substantially at right angles to the ravel edge, whereby coursewise and walewise topping lines can be provided in parallel relation to the ravel and heel tab edges respectively, some of the wales between the walewise topping line and said heel tab edge being interlocked with adjacent wales at a course below said ravel edge topping line by means of transferred loops.

3. In a full fashioned stocking blank comprising a leg portion knitted from a plurality of transverse courses, spaced heel tabs knitted from a plurality of transverse courses onto the lower

edge of the leg portion, said tabs being formed by the continuation of the wales of the leg portion and having the proximate edges thereof substantially parallel thereby forming a corner at the junctions of the heel tab edges and the lower edge of the leg portion, whereby coursewise and walewise topping lines can be provided in parallel relation to the lower edge of the leg portion and heel tab edges respectively, reinforcing strands knitted into said leg and heel portions and extending inwardly in a coursewise direction from the edge of the blank through the wales which form said heel tab edges, some of the reinforced wales of the leg portion being interlocked with adjacent wales along the heel tab edges by means of transferred loops.

4. In a full fashioned stocking blank comprising a leg portion knitted from a plurality of transverse courses, spaced heel tabs knitted from a plurality of transverse courses onto the lower edge of the leg portion, said tabs being formed by the continuation of the wales of the leg portion and having the proximate edges thereof substantially parallel thereby forming a corner at the junctions of the heel tab edges and the lower edge of the leg portion, whereby coursewise and walewise topping lines can be provided in parallel relation to the lower edge of the leg portion and heel tab edges respectively, each side of the lower leg portion having a reinforcing strand knitted into said leg and also knitted into the adjacent heel portion and extending inwardly in a coursewise direction from the edge of the blank beyond the wales which form said heel tab edges, the terminal loops of the reinforced wales in the leg portion which are adjacent the inner edges of the heel tabs edges being transferred and locked in adjacent wales along said heel tab edges, in a subsequent course knitted below the coursewise topping line.

5. In a full fashioned stocking blank comprising a leg portion knitted from a plurality of transverse courses, spaced heel tabs knitted from a plurality of transverse courses onto the lower edge of the leg portion, said tabs being formed by the continuation of the wales of the leg portion and having the proximate edges thereof substantially parallel thereby forming a corner at the junctions of the heel tab edges and the lower edge of the leg portion, whereby coursewise and walewise topping lines can be provided in parallel relation to the lower edge of the leg portion and heel tab edges respectively, each of said leg and heel portions having a reinforced strand knitted thereto and extending in a coursewise direction from the edge of the blank beyond the wales which form said heel tab edges, terminal loops of the reinforced wales in the leg portion which are disposed inwardly beyond the heel tab edge being transferred outwardly and locked in one of the wales along the heel tab edge.

6. Full fashioned hosiery construction, comprising a leg portion, a heel tab attached to the leg portion thereby forming a corner at the junction of the edge of the leg portion and the heel tab edge, and transferred terminal loops connecting said edges at said corners.

7. Full fashioned hosiery construction comprising a leg portion, spaced heel tabs knitted onto the leg portion, thereby forming corners at the junctions of the unselvedged edge of the leg portion and the proximate selvedged edges of the tabs, some of the loops of the unselvedged edge being locked along the heel tab edges.

8. In a full fashioned stocking blank compris-

ing a leg portion knitted from a plurality of transverse courses, spaced heel tabs knitted from a plurality of transverse courses onto the lower edge of the leg portion, said tabs being formed by the continuation of the wales and the leg portion and having the proximate edges thereof substantially parallel thereby forming a corner at the junctions of the heel tab edges and the lower edges of the leg portion, each side of said leg portion and each heel tabs comprising a body strand and a reinforcing strand at each of said corners, a reinforced stepped area abridging each of said corners, said area being formed by extending knitted courses inwardly beyond the proximate edges of the heel tabs and below the lower edge of the leg portion, the loops along the unselvedged edge of the stepped area being locked by the transfer of the loops to the heel tab.

9. In a full fashioned stocking blank comprising a leg portion knitted from a plurality of transverse courses, spaced heel tabs knitted from a plurality of transverse courses onto the lower edge each side of the leg portion, said tabs being formed by the continuation of the wales of the leg portion and having the proximate edges thereof substantially parallel thereby forming a corner at the junctions of the heel tab edges and the lower edges of the leg portion, each side of the lower leg portion and heel tabs comprising a body strand and a reinforcing strand at each of said corners, the loops formed from the combined strands at each corner along the unselvedged edge of the leg portion being locked to said heel tabs, by means of a plurality of successive transfers. 35

10. Full fashioned hosiery construction comprising a leg portion, spaced heel tabs knitted onto the lower edge of the leg portion, reinforcing strands knitted into each side of the lower leg portion, the terminal loops of the lower leg portion adjacent the inner edges of the heel tabs being transferred to the heel tabs.

11. In a full fashioned stocking blank comprising a leg portion knitted from a plurality of transverse courses, spaced heel tabs knitted from a plurality of transverse courses onto the lower edge of the leg portion, said tabs being formed by the continuation of the wales of the leg portion and having the proximate edges thereof substantially parallel, thereby forming a corner at the junctions of the heel tab edges and the lower edge of the leg portion, and transferred loops connecting the terminal loops of the leg portion and the adjacent inner edges of the heel tabs. 15

12. Full fashioned hosiery construction comprising a leg portion, spaced heel tabs knitted onto the leg portion thereby forming corners at the junctions of the unselvedged edge of the leg portion, and the proximate selvedged edges of the tabs, said leg portion and heel tabs comprising a body strand and a reinforcing strand for each side of the leg portion and each heel tab, the loops formed from the combined strands along the unselvedged edge of the leg portion being interlocked with adjacent wales of the heel tabs by transferred loops at a course below said unselvedged edge. 20 25 30
